WINDOW VENTILATOR

Walter A. Spear, Cincinnati, Ohio, assignor to
Victor Electric Products, Inc., Cincinnati, Ohio,
a corporation of Ohio

Application April 16, 1946, Serial No. 128,640

Term of patent 14 years

(Cl. 62—4)

To all whom it may concern:

Be it known that I, Walter A. Spear, a citizen of the United States, residing at Cincinnati, in the county of Hamilton and State of Ohio, have invented a new, original, and ornamental Design for Window Ventilator, of which the following is a specification, reference being had to the accompanying drawing, forming part thereof.

In the drawings,

Figure 1 is a front elevational view of a window ventilator, showing my new design.

Figure 2 is a top plan view thereof.

Figure 3 is a side elevational view thereof.

Figure 4 is a cross sectional view of the grill, taken substantially on the line 4—4 of Figure 1.

Figure 5 is another cross sectional view of the grill, taken substantially on the line 5—5 of Figure 1.

The dominant features of my design reside in the portion shown in full lines.

I claim:

The ornamental design for a window ventilator, as shown and described.

WALTER A. SPEAR.
